UNITED STATES PATENT OFFICE.

ARTHUR McILVAIN MARIS, OF PHILADELPHIA, PENNSYLVANIA, ASSIGNOR TO DUPONT MOTORS, INC., OF WILMINGTON, DELAWARE, A CORPORATION OF DELAWARE.

DESIGN FOR AN AUTOMOBILE-RADIATOR.

57,140.

Specification for Design.

Patented Feb. 22, 1921.

Application filed December 23, 1919. Serial No. 347,023. Term of patent 14 years.

To all whom it may concern:

Be it known that I, ARTHUR McILVAIN MARIS, a citizen of the United States, residing in Philadelphia, county of Philadelphia, State of Pennsylvania, have invented a new, original, and ornamental Design for Automobile-Radiators, of which the following is a specification, reference being had to the accompanying drawing, which forms a part hereof.

The figure is a front view of a radiator embodying my invention.

I claim—

The ornamental design for an automobile radiator, as shown.

In testimony of which invention, I have hereunto set my hand, at Wilmington, Del., on this twenty-ninth day of November, A. D. 1919.

ARTHUR McILVAIN MARIS.
